US00D549565S

(12) **United States Design Patent** (10) **Patent No.:** **US D549,565 S**
Cox et al. (45) **Date of Patent:** **** Aug. 28, 2007**

(54) **CLIP**

(75) Inventors: **Johnny Cox**, Rowlett, TX (US); **Trevor Jackson**, Kirtland, OH (US); **Harry Klaus**, Mars, PA (US)

(73) Assignee: **Emerald Innovations L.L.C.**, Butler, PA (US)

(**) Term: **14 Years**

(21) Appl. No.: **29/253,311**

(22) Filed: **Feb. 3, 2006**

(51) **LOC (8) Cl.** **08-08**

(52) **U.S. Cl.** **D8/394**

(58) **Field of Classification Search** ..... D8/356, D8/371, 394-396; D19/65; 24/22, 67 R, 24/20 S, 115 R, 546, 563, 910, 343, 67.9; 248/74.2, 215, 227.1, 49, 300, 301, 316.7, 248/51, 489
